UNITED STATES PATENT OFFICE.

MARTIN L. NELSON, OF PARK RIDGE, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed June 12, 1924, Serial No. 719,459. Renewed March 7, 1928.

The present invention relates to automatic telephone systems in general, but is concerned more particularly with automatic telephone systems in which directors are employed to 5 register, translate and retransmit telephone numbers.

As to certain of its features, this case is concerned more particularly with a system in which there are several main exchanges 10 and two or more subexchanges, while as to certain other features it relates to systems in which the telephone numbers vary considerably amongst themselves as to the number of digits they contain.

15 One object is the provision of simple and efficient arrangements in a director for causing the director to be cut off at the termination of the transmission of the last digit regardless of the number of digits contained in 20 the registered number.

Another object is the production of new and improved circuit arrangements whereby all 25 code digits which are normally transmitted in accordance with the setting of the office register are cancelled at the end of the office registration, and the sending mechanism is prevented from starting until a subscriber digit is registered.

It is a further object to provide a new and 30 improved vibrating interrupter for generating the impulses transmitted by the sender.

There are several other objects and features of the invention which can be understood best from a perusal of the detailed description which is to follow.

Referring now to the drawings, Fig. 1 is a map showing the relative positions and the relative sizes of the various offices of the exchange; Figs. 2 and 3 show a trunking diagram which is sufficiently complete to enable 40 the entire inter-office trunking net-work, as well as the trunking local to each office, to be understood; Figs. 4-10, inclusive, are circuit drawings showing all the apparatus involved 45 in a call from a subscriber in Meadow at one end of the net-work to a subscriber in Irving at the other end of the net-work (see Fig. 1); and Figs. 11-13, inclusive, are mechanical drawings of the improved vibrating interrupter used in connection with the sending 50 equipment of the director.

Referring now particularly to Fig. 1, the Edgewater, Pontiac, Centre, Main and Market offices are all main offices in a direct trunk 55 net-work of the usual multi-office type. The

Cedar and Meadow offices, on the other hand, may be considered as satellites of the Edgewater office, and in the same way the Irving and Augusta offices may be considered as satellites of the Main office. All of the offices 60 shown are automatic offices except Irving and Augusta which are manual offices.

The inter-office trunking between the various main offices of the system, of course, presents no difficulty, and no directors are used 65 in the main offices. Consequently, the only place where directors are used is in the satellite offices Cedar and Meadow, and they are used there in order to permit the so-called Universal numbering system, that is, a system 70 in which any one subscriber's number remains the same regardless of from which station it is called. Also, the directors do not enter into the consideration of calls coming in to Cedar and Meadow by way of Edgewater, and it is only on calls actually originated 75 in Cedar or Meadow that directors are used, as will be pointed out hereinafter.

Referring now particularly to the trunking diagram shown in Figs. 2 and 3, this diagram shows the trunking in the main offices Edgewater and Main and in the satellite offices Meadow and Cedar, and shows how calls are completed from main to the manual offices Irving and Augusta. Considering first the 80 office Edgewater, a calling line, for example the line of substation A², is connected by the associated line switch LS² to an idle first selector, for example the first selector S²². In case the first digit dialled by the calling sub- 85

scriber is the digit 3, the first selector S²² extends a connection to a local thousands selector, such as the selector S²³, and the second digit determines whether call is going to be completed to a local subscriber in Edgewater, 90 or is going to be extended by way of a repeater such as R¹⁰ to Cedar in case the second digit dialled is the digit 0. In case the call is extended to Cedar by way of the repeater R¹⁰ the selector S¹⁰ in Cedar responds to the 95 third digit dialled and selects a local selector in Cedar if the third digit is 5 or under, for example one of the selectors S¹⁶-S²⁰, inclusive, but, if the third digit dialled is 6, 7, 8 or 9, an outgoing trunk is seized and a connection is extended by way of a repeater, 100 such for example as one of the repeaters R⁵-R⁸, inclusive, to an incoming selector in Meadow, such as one of the incoming selectors S⁶-S⁸, inclusive. The next digit dialled picks 105

a local connector in Meadow, and the next two digits extend the connection to the called line.

When a call is extended from Edgewater to Main by way of, for example, the repeater R¹⁵ it comes in at Main on the incoming selector S³³, and, upon the dialling of the next digit, a local thousands selector, such as the selector S³⁵, is seized in case the second digit is 9 or under, but if the second digit is 0 a special selector, such as S³⁶, is seized and the call is extended to one of the manual offices Irving or Augusta by way of a repeater, such as R²⁵ or R²⁶.

Considering now calls originated in Main, when the first selector S²⁹ is seized the call is extended to a local thousands selector, such as S³¹, if the first digit dialled is 6, and is thereafter extended to a local line or to a line in Irving or Augusta, depending upon whether the second digit is 0 or some other digit. On the other hand, if the first digit dialled is 3, 4, 5 or 7 the connection is extended by way of a repeater, such as the repeaters R²¹-R²⁴, inclusive, to one of the other main offices, and if the digit is 3 the call may be extended by way of the repeater R²⁴ to the incoming thousands selector S²⁴ in the Edgewater office and is thereafter completed locally or is trunked to Cedar if the next digit dialled is 0.

Considering now calls originated in Meadow, when the line of substation A is calling the line switch LS selects an idle selector such as S and the director selector DS associated with the trunk circuit TC selects an idle director. In case the first digit dialled is 3, the second digit is 0 and the third digit is 6, 7, 8 or 9, the director does not transmit any digit in response to the reception of the first two digits 3 and 0, but transmits the third digit received as the first digit of the number and the selector S selects a local selector, such as the selector S', S², S³ or S⁴, and the call is extended to a local line in Meadow. On the other hand, if the third digit is 5 or under, instead of the digits named, the connection is extended by way of a repeater, such as the repeaters R-R⁴, inclusive, to one of the incoming selectors S¹¹-S¹⁵, inclusive, in the nearby satellite office Cedar and is there completed locally by way of one of the selectors named. On the other hand, as will be pointed out more in detail hereinafter, if the first two digits received by the director are not 3 and 0 but are digits which indicate that the desired line terminates in one of the main offices or in one of the manual offices of the system, the director automatically transmits the code digits 3 and 0, followed by the registered number of the called line. Responsive to the transmission of the code digit 3 by the director, the selector S extends the connection by way of a repeater in the third group such as the repeater R² to an incoming selector S¹³

in Cedar, which responds to the second code digit 0 and extends the connection by way of a repeater such as R⁹ to the incoming office selector S²¹ in Edgewater. From this point the connection is completed just as though the calling subscriber were a local subscriber in Edgewater.

Considering now calls originating in Cedar, when the subscriber at substation at A' is calling the line switch LS' extends the connection to an idle selector such as the selector S⁹, and the director selector DS' associated with the trunk circuit TC' selects an idle director. In case the first two digits dialled are 3 and 0 the director does the same as the director in Meadow, omitting the first digits and re-transmitting the remaining digits to complete the connection in one of the satellite offices Meadow and Cedar.

In case the first two digits indicate that the calling line is reached by way of one of the main offices of the system, the director transmits the code digit 0 and then repeats the registered number. The transmission of the code digit 0 results in the connection being extended by way of a repeater such as the repeater R⁹ to the incoming selector S²¹ in Edgewater, from which point the connection is extended just as though the calling subscriber were a local subscriber in Edgewater.

Considering now the circuit drawings comprising Figs. 4-10, inclusive, Figs. 4, 5 and 6 show the trunking equipment necessary to extend a connection from the subscriber at substation A in Meadow to the subscriber at substation A' in Irving. This connection, when established, includes the line switch LS, the trunk circuit TC, the selector S, and the repeater R in Meadow; the selector S¹³ and the repeater R⁹ in Cedar; the selector S²¹ and the repeater R¹⁵ in Edgewater; the selectors S³³ and S³⁶ and the repeater R²⁵ in Main; and the cord circuit CC and the jack J in Irving.

It will be noted that the circuits of the selectors S¹³, S²¹, S³³ and S³⁶, Fig. 5, are not shown. The circuits of these selectors, it may be pointed out, may be similar to the circuit of the selector S, Fig. 4. Also, it will be noted that the circuits of the repeaters R⁹ and R¹⁵, Fig. 5, and the repeater R²⁵, Fig. 6, are not shown. The circuits of these repeaters may be the same as the circuit of the repeater R, Fig. 5.

It is thought that nothing further need be said about the trunking arrangement at this point, and it will suffice to point out that the line switch LS is, mechanically, of the well known rotary type, and that its wipers have no normal position but are moved in a forward direction only and are advanced upon the back stroke of the associated stepping magnet rather than upon the front stroke. The director selector DS is a non-numerical

trunk hunting switch and, from a mechanical standpoint, is similar to the line switch LS. The selector S is a standard two-wire selector from a circuit standpoint, and mechanically, 5 is of the well known vertical and rotary type and its bank contacts are arranged in horizontal rows or levels.

Referring now to the director shown in Figs. 7-10, inclusive, this director comprises 10 essentially an office register OR which is a vertical and rotary switch of the usual type and which registers the first two digits of a number, together with the so-called digit registers DR¹-DR⁴, inclusive, Fig. 10, and 15 the sender, Fig. 8. The sequence switch S, Fig. 7, distributes the various impulses in the called number amongst the various registers. The first two series of impulses are transmitted to the vertical and rotary magnets, respectively, of the office register OR, 20 Fig. 9, and the remaining series are distributed to the various digit registers DR¹-DR⁴, inclusive, Fig. 10.

Although only one set of bank contacts is 25 shown associated with the office register OR it will be understood that there are one hundred such sets of bank contacts and that each set of bank contacts is connected to the right hand side of the intermediate distributing 30 frame IDF in the same manner as the set shown.

The function of the sequence switch S', Fig. 7, is primarily to associate the sender first with the office register OR until the office 35 code is transmitted, and then with the various digit registers shown in Fig. 10 in order until the subscriber digits of the number are sent out after which the sequence switch is again advanced to cause the trunk circuit TC, Fig. 40 4, to switch through and the director to be freed.

Referring now particularly to Figs. 11, 12 and 13, these drawings show three views of the new and improved vibrating interrupter. 45 Fig. 11 is a front view of the interrupter; Fig. 12 is a view from the right side; and Fig. 13 is a rear view. This interrupter comprises, essentially, the magnet coil 2 and the reed 5 which is excited by the magnet coil 2 and controlled in its period of vibration by the weight 6.

The core of the coil 2 is provided with the soft iron poles 3 and 4, which, together with the spring steel reed 5, form the return magnetic circuit. The small strip of brass 15 is secured to the end of the pole piece 4 in order 55 to prevent the reed 5 from coming close enough to the pole piece 4 to stick. The reed 5 carries a contact which engages with a similar contact on the spring 7 when the reed 5 is attracted toward the core. These contacts are used for short circuiting the winding 2 when the reed 5 is attracted so as to cause the winding to deenergize and permit the reed to 65 swing away again. The point at which the

short circuiting contacts close may be adjusted by the screw 12 which is provided with a lock-nut 13 to hold it in its adjusted position. The insulated tip of the screw 12 bears against the spring 7.

The interrupter springs 8 and 9 are provided with contacts which are normally in engagement with each other, but when the reed 5 swings outward it strikes the bushing 16 moving the spring 9 far enough to cause 70 the associated contact to break away from the contact of the spring 8. These contacts then close again when the reed 5 swings in for the next stroke. The point at which the interrupter contacts open and close may be 75 adjusted by the screw 14 which is provided with a lock-nut for holding it in its adjusted position. The unthreaded portion of the screw 14 passes through a hole in the spring 9 and its insulated tip rests against the spring 8 holding the latter at the desired point. The spring 17 is provided to limit the forward 80 movement of the pendulum bob 6 so as to limit the amplitude of the vibrations.

The system having been described generally, the detailed description of the operation of the apparatus will now be given. For this purpose it will be assumed that the subscriber at substation A, Fig. 4, whose line terminates in Meadow, Figs. 1 and 2, desires to call the 95 manual subscriber at substation A⁴, Fig. 6, whose line terminates in Irving, Figs. 1 and 3.

When the receiver is removed at substation A, a circuit is closed over line conductors 401 and 402 for line relay 405 of the line switch 100 LS. Line relay 405 thereupon energizes and places ground upon private normal conductor 403 at armature 409, thereby making the calling line busy to the connectors having access to it and closing a circuit through switching relay 404 and stepping magnet 411 in series. At armature 410 line relay 405 also connects test wiper 413 to the junction of switching relay 404 and stepping magnet 411. In case the trunk upon which the wipers 110 412-414 of the line switch LS are standing is idle, this latter operation of line relay 405 is not of any particular utility and switching relay 404 energizes, seizing the 115 trunk.

Assuming, however, that the trunk upon which the wipers of the line switch are standing is busy, switching relay 404 is short circuited by the ground potential encountered by test wiper 413 and does not energize. 120 Stepping magnet 411 energizes through the grounded test wiper 413 and operates the wipers 412-414, inclusive, step by step in search of an idle trunk by its buzzer-like action.

When an idle trunk is reached, which trunk, it will be assumed, is the one comprising conductors 415-417, inclusive, switching relay 404, being no longer short circuited, energizes in series with stepping magnet 411; 130

opens the test circuit and prepares the holding circuit at armature 407; and at armatures 406 and 408 disconnects line conductors 401 and 402 from line relay 405 and ground and 5 extends them by way of wipers 412 and 414, conductors 415 and 417, and armatures 430 and 433 to the upper and lower windings, respectively, of the double wound relay 421 of the trunk circuit TC. Line relay 421 now 10 energizes over the calling line and closes a circuit for release relay 422 at armature 425. Release relay 422 now energizes in series with resistance 424 and places ground upon release trunk 416 at armature 423, thereby closing 15 the usual holding circuit for switching relay 404 of the line switch LS before the slow acting relay 405 has had time to deenergize.

In the trunk circuit TC, as a further result of the energization of release relay 422, it 20 prepares the operating circuit at armature 427; closes a circuit for switching relay 439 and stepping magnet 440 of the director selector DS in series at armature 428; and at armature 429 connects the test wiper 443 of 25 the director selector DS to the junction of switching relay 435 and stepping magnet 440. Accordingly, the director selector DS operates in the manner just described for the line switch LS and selects an idle director. When 30 an idle director is selected, which director it will be assumed is the one reached by way of conductors 449-452, inclusive, switching relay 435 energizes; opens the test circuit and grounds test wiper 443 at armature 438; closes 35 a further point in the operating circuit at armature 439; and at armatures 436 and 437 connects up wipers 441 and 442 thereby placing a closed loop across conductors 445 and 448 of the selector S. This loop includes wipers 441 and 442, conductors 449 and 450, resting contact and armature 481, and the resting contact and armature 484 and contacts 813 in multiple. Accordingly, line relay 461 of 40 the selector S energizes through the resting contacts and armatures 472 and 475, and closes a circuit for release relay 462 at armature 466. Release relay 462 thereupon energizes, grounds release trunk conductor 447 at armature 467; and at armature 468 opens a 45 point in the circuit of release magnet 479 and prepares a circuit for vertical magnet 480.

In the seized director, release relay 806, Fig. 8, energizes through armature 832 and its resting contact responsive to release trunk conductor 451 being grounded by the director selector DS, Fig. 4, as above pointed out. Upon energizing, relay 806 connects up the timing lead 804 at armature 839; prepares a locking circuit for relay 808 at armature 838; at armature 836 disconnects the bank of wiper 819 of the counting switch CS from relay 805 and connects it to ground; disconnects release conductors 730 and 743 at armatures 834 and 835, respectively; opens the normal restoring 60 circuit of the sender at armature 833; and at 65

armature 837 closes a circuit for the interrupter 811 and relay 810 in series, thereby starting the interrupter to operate so as to have it running at a steady rate when it comes into play. The pendulum 812 is attracted 70 when the above circuit is closed, but the marginal relay 810 is not operatively energized on account of the high resistance of the magnet of the vibrating interrupter 811. Upon its inward swing the reed 812 engages a contact 75 which short circuits the winding 811, whereupon the reed swings outward again and opens the contacts 813 upon the outward swing. When the winding of the interrupter 811 is short circuited the marginally adjusted 80 relay 810 energizes and operates armature 849 for a purpose to be explained hereinafter.

As pointed out hereinbefore, a second point in the operating circuit was closed at armature 439. Fig. 4, upon the energization of 85 switching relay 435 of the director selector DS. When this occurs the vertical magnet of the office register OR, Fig. 9, is connected in multiple with the resistance 424 through armature 427 of relay 422 and its working contact, armature 439 and its working contact, wiper 444, conductor 452, armature 850 and its resting contact, conductor 725, contacts 904, conductor 733, series relay 702, conductor 739, resting contact and armature 916, armature 923 and its resting contact, wiper 719 of the sequence switch S and its first contact, and conductor 741. Vertical magnet 909 is not energized over this circuit, however, on account of the high resistance of release relay 90 422 of the trunk circuit TC.

Vertical magnet 909 of the office register 95 OR, Fig. 9, is connected to battery through the right hand winding of the common dial tone transformer 908. Accordingly, the tone 100 from the dial tone machine is transmitted back over the circuit just traced to the condenser 434, Fig. 4, which is provided in order 105 to enable the dial tone current to pass to the talking circuit through the resting contact 110 and armature 433 to inform the calling subscriber that he may now dial the number.

In order to explain one feature of the invention, it will be assumed that the subscriber at substation A is called away from the telephone and does not replace his receiver. Accordingly, if special provisions were not made, the director would remain tied up and an expensive piece of equipment would be put out of service, so to speak, as regards handling 115 calls for other subscribers. In order to prevent this a timing arrangement has been provided which will cause the trunk circuit TC to be switched through and the director to be freed in case the first digit of the number is 120 not dialled within a predetermined time. The circuits through which this timing apparatus functions are carried through the off 125 normal contacts of the office register OR, Fig. 9, so as to enable the director to be cut off 130

without transmitting any number in case the delay occurs before the first digit is dialled, and to enable a special number to be sent out in case a delay occurs between the dialling of 5 any two subsequent digits, as will be explained hereinafter. To continue with the description, it will be remembered that the common timing conductor 804, Fig. 8, was connected up at armature 439 upon the energization of release relay 806. Accordingly, upon the first closure of the contacts associated with the slow interrupter 803, ground is extended through armature 839 and its working contact, resting contact and armature 10 852, armature 847 and its resting contact, to the upper winding of the two-step relay 808. Relay 808 thereupon energizes part way only on account of the fact that its upper winding is composed of a small number 15 of turns of wire having a relatively high resistance. Accordingly, its first step armature 806 is operated but its second step armature 847 remains in its normal position. Upon being operated, armature 846 closes a 20 locking circuit for relay 808 as follows: from ground by way of armature 706 of relay 702, Fig. 7, and its resting contact, conductor 735, conductor 860, armature 838 and its working contact, armature 846 and its working contact, and the two windings of relay 808 in 25 series. This locking circuit is not effective at this time, however, on account of the fact that the initial circuit is still established. A short time later the contacts of the interrupter 803 open again, opening the initial circuit of relay 808, whereupon the locking circuit through the two windings in series becomes effective, and the relay operates fully. Accordingly, armature 847 opens a further 30 point in the initial circuit of the upper winding of the relay and prepares a circuit for switching relay 814. After an interval of say one minute the slow interrupter 803 closes its associated contacts again, thereby completing a circuit through armature 839 and its working contact, resting contact and armature 852, armature 847 and its working contact, normally closed contacts controlled by armature 845, conductor 862, off normal 35 spring 907 and its resting contact of the office register OR, Fig. 9, switching conductor 731, normally closed contacts controlled by armature 853, and switching relay 814 to battery. Switching relay 814 now energizes and locks 40 itself to the grounded release trunk conductor 451 and opens its initial circuit at armature 853, and at armature 850 disconnects the combined switching and operating conductor 452 from conductor 725 and connects it to ground, thereby completing a circuit over conductor 452 and through wiper 444 of the director selector DS, working contact and armature 427, and the normally open contacts controlled by armature 425 for the switching 45

lay 423 of the trunk circuit TC. Switching relay 423 now energizes and locks itself to the grounded release trunk conductor 447 at armature 453; connects release trunk conductor 416 to the release trunk conductor 447 50 at armature 432; removes battery from vertical magnet 480 of the selector S at armature 431; and at armatures 430 and 433 disconnects conductors 415 and 417 from line relay 421 and connects them instead to conductors 445 55 and 448 of the selector S, at the same time disconnecting the latter from the control loop of the director. Line relay 461 of the selector S is now maintained energized over the calling line, but the vertical magnet 480 60 cannot be operated in case the calling subscriber returns to the phone and manipulates his calling device, because battery is removed from the vertical magnet 480 at armature 431.

Responsive to being disconnected, line relay 421 of the trunk circuit TC falls back and short circuits the associated release relay 422 which, accordingly, deenergizes after a slight interval and opens the circuit of switching relay 435 of the director selector DS at armature 428, whereupon relay 435 deenergizes, freeing the director.

It will now be assumed that the calling subscriber is not called away from his telephone and that he hears the dial tone impressed upon his line through the vertical magnet of the office register OR, Fig. 9, in the hereinbefore described manner, and dials the first digit 6 in the desired number. Accordingly, when the calling device is operated six interruptions are produced in the circuit of line relay 421 of the trunk circuit TC, which line relay is accordingly deenergized six times momentarily. Upon each deenergization of line relay 421 the switching 100 relay 423 is disconnected to prevent it from being operated at this time, and release relay 422 is short circuited at the contacts controlled by armature 425. Release relay 422 does not deenergize during this operation 105 owing to the fact that it is short circuited and its circuit is not opened, making it slow acting as is well known. Each time release relay 422 is short circuited a ground potential is extended through armature 427 and 110 its working contact, armature 439 and its working contact, and wiper 444 to the operating conductor 452, thereby closing a circuit over the previously traced path to vertical magnet 909 of the office register OR, 115 Fig. 9, through wiper 719 of the sequence switch S, Fig. 7. Accordingly, vertical magnet 909 is energized six times momentarily and, upon each energization, raises the wipers 941-944, inclusive, one step, resulting in the 120 said wipers being raised opposite the sixth level of bank contacts.

Upon the first upward step of the wipers of the office register, the off normal contacts 906 are closed, connecting the spark condenser 130

908 to conductor 733 which is connected to the impulse distributing wiper 719 of the sequence switch S, through series relay 702 and armatures 916 and 923. Accordingly, 5 the spark which would otherwise be produced upon the opening of the circuit of vertical magnet 909 and series relay 702 is quenched by the condenser 908. It may be pointed out that this condenser is not normally connected 10 to the operating circuit because if it were the dial tone impressed upon the operating circuit through vertical magnet 909 would be practically short circuited by the fairly heavy condenser 908.

15 Relay 702 is energized in series with vertical magnet 909 upon the first impulse of current delivered to the latter, and, being slow acting, maintains its armature attracted throughout the vertical movement. Upon 20 energizing, relay 702 closes at armature 706 a circuit for the slow acting relay 701 which thereupon energizes and prepares at armature 705 a circuit for the operating 717 of the sequence switch S. Accordingly, when 25 series relay 702 deenergizes at the end of the first series of impulses, it closes at armature 706 a circuit for magnet 717, through the working contact and armature 705, whereupon magnet 717 energizes and advances the 30 wipers 718 and 719 one step, and wiper 719 shifts the operating circuit from the vertical magnet of the office register to the rotary magnet. Relay 702 also opens the circuit of the slow acting relay 701 which de- 35 energizes an instant later, opening the circuit of magnet 717 at armature 705.

When the calling subscriber dials the second digit 0 in the desired number, ten impulses of current are sent to the director over the operating circuit to the impulse distributing wipers 719 of the sequence switch S and then over conductor 742 to the rotary magnet 910 of the office register OR. By 40 the operation of the rotary magnet 910 the wipers of the office register OR are rotated step by step until they come into engagement with the tenth set of bank contacts in the sixth level, which is the set of contacts shown in the drawings. Series relay 702 is 45 energized over the operating circuit as before and, together with the associated slow acting relay 701, causes the advance of the sequence switch S at the end of the series of impulses in the hereinbefore described manner.

Responsive to the dialling of the third digit 1 in the desired number, one impulse of current is delivered over the operating circuit to wiper 719 of the sequence switch S and is then transmitted through series relay 712 and conductor 751 to the stepping magnet 1004 of the digit register DR¹, Fig. 10, which thereupon energizes and advances the wiper 1005 into engagement with the first associated bank contact.

The wipers 719 and 718 of the sequence switch S are again advanced one step in the usual manner, and wiper 719 connects the operating circuit through conductor 752 to the stepping magnet of the second digit register DR², Fig. 10. However, the automatic subscribers are instructed not to dial the last three digits in the manual numbers and to wait until the operator answers and then give her the complete desired number. Accordingly, the subscriber at substation A does not dial any further digits at this time.

Returning now to the point at which the wipers 718 and 719 of the sequence switch S were advanced into engagement with the 80 third set of associated bank contacts at the end of the rotary movement of the office register OR, the operation of the office register OR has been completed at this time and the sender may now be started. Accordingly, wiper 718 85 of the sequence switch S, upon coming into engagement with its third associated bank contact, places ground upon the start conductor control wiper 722 of the sequence switch S', wiper 718 being grounded over conductor 90 727 and through the resting contact and armature 840 of relay 807, Fig. 8.

Responsive to the ground potential being placed upon wiper 722, a circuit is closed through the first contact in the bank of wiper 95 722 and through the resting contacts and armature 708 and start conductor 738 for the stepping magnet 817 of the counting switch CS, Fig. 8, by way of the resting contact and armature 849 of the marginal relay 810, and armature 851 and 859. Upon the next deenergization 100 of stepping relay 810, a circuit is closed at armature 849 for the stepping magnet 817 of the counting switch CS. Stepping magnet 817 thereupon energizes and advances the 105 associated pawl into engagement with the next notch in the wiper driving ratchet wheel but does not move the wipers 819 and 820. Upon the following energization of stepping relay 810 the circuit of stepping magnet 817 110 is again opened whereupon the said magnet 817 deenergizes and advances the wipers 819 and 820 one step in a counter clockwise direction, whereupon pick-up relay 815, which is connected to the pick-up wiper 819, energizes through the first grounded contact in the pick-up bank and armature 836 and its working contact; prepares a locking circuit for stop relay 816 at armature 855; and at armature 854 removes the shunt from around 115 the sending contacts 813 of the vibrator 811. This occurs at about the time the pendulum 812 is in its extreme left position and the contacts 813 are closed.

When the pendulum 812 subsequently 125 swings to the right, it removes the shunt from around the winding 811 and permits relay 810 to deenergize and close the circuit of stepping magnet 817 again at armature 849, and at armature contacts 813 the pendulum 130 812

opens the outgoing control circuit. At the end of this interruption in the control circuit the coil 811 is again short circuited and the relay 810 again energizes to open the circuit 5 of the stepping magnet 817, whereupon the said stepping magnet 817 again deenergizes and the wipers 819 and 820 are advanced another step. Wiper 820, accordingly, engages a contact in which the first impulse stop conductor terminates. However, since this conductor is not grounded at this time the stop relay 816 is not energized. This operation continues as described under the control of the interrupter 811 and the wipers 819 and 820 continue to be advanced one step after 10 each opening in the outgoing control circuit at contacts 813 until five interruptions have been produced in the outgoing control circuit, at which time wiper 820 is in engagement 15 with the bank contact in which the second impulse stop conductor 952 terminates. Now, when the pendulum 812 swings to the left again it closes the outgoing impulse control circuit at contacts 813 and short circuits the 20 winding 811 resulting in the circuit of magnet 817 being opened at armature 849, whereupon wiper 820 is advanced into engagement with the bank contact in which the third impulse stop conductor 953 terminates, thereby 25 closing a circuit for stop relay 816 as follows: From ground by way of the grounded stop conductor control wiper 724, the first associated bank contact, stop conductor 761, wiper 941 of the office register OR, bank 30 contact 961, jumper 971 on the intermediate distributing frame IDF, the third impulse stop conductor 953, the corresponding contact in the bank of wiper 820, wiper 820, and stop 35 relay 816 to battery. Stop relay 816 now energizes over this circuit and closes a locking circuit for itself at armature 858; disconnects stepping magnet 817 at armature 859; shunts the impulse contacts 813 at armature 856; and at armature 857 closes the automatic 40 restoring circuit for the counting switch CS. 45

It will be noted that the stepping magnet 720 of the sequence switch S' is connected in multiple with stop relay 816, Fig. 8, through conductor 726. Accordingly, upon the 50 previously mentioned closure of the circuit of stop relay 816, initially, a circuit is closed for stepping magnet 720 which accordingly energizes in preparation for the advance of the wipers 722, 723 and 724.

55 The counting switch CS is now advanced to its normal position by the buzzer-like action of the self-interrupting stepping magnet 817, which operates through the interrupter contacts 818, armature 857 and its working contact, wiper 819, the associated bank of contacts and armature 836 and its working contact. The restoring circuit is broken and the circuit of pick-up relay 815 is opened when wiper 819 passes off the last 60 grounded bank contact. Pick-up relay 815,

however, does not deenergize right away because it is slow acting.

In the selector S, Fig. 4, line relay 461 deenergizes responsive to each of the three interruptions produced in the outgoing 70 control circuit in the director, and upon each deenergization completes at armature 466 a circuit through armature 468 and its working contact and series relay 463 for vertical magnet 480. By the operation of vertical magnet 480 the wipers 482-484, inclusive, are raised step by step and come to rest opposite the third level of bank contacts. Relay 463 is energized in series with vertical magnet 480 and, being slow acting, maintains its armature attracted throughout the vertical movement. Upon energizing, relay 463 closes at armature 469 a circuit for stepping relay 464 through the off normal contacts 481 which close upon the first vertical step and the interrupter contact 477. Upon energizing, stepping relay 464 closes a locking circuit for itself at armature 470, and at armature 471 prepares a circuit for rotary magnet 476. 85

90 At the end of the vertical movement slow acting series relay 463 falls back and completes at armature 469 the circuit of rotary magnet 476 which thereupon energizes and advances the wipers 482-484, inclusive, into engagement with the first set of contacts in 95 the third level and, near the end of its stroke, opens the circuit of stepping relay 464 at contacts 477. Stepping relay 464 now deenergizes and opens the circuit of rotary magnet 476 at armature 471, whereupon rotary magnet 476 deenergizes also and closes its interrupter contacts 477 again.

100 In case the trunk terminating in the first set of bank contacts is idle, switching relay 465 energizes seizing the trunk. Assuming, however, that the trunk is busy, switching relay 465 is short circuited by the ground potential encountered upon the busy test contact by test wiper 483 and does not energize, and stepping relay 464 energizes through test wiper 483 and closes a circuit for rotary magnet 476 at armature 471, whereupon rotary magnet 476 energizes again advancing the wipers into engagement with the next set of bank contacts. 115

120 This alternate operation of stepping relay 464 and rotary magnet 476 continues as described until an idle trunk is reached, which trunk it will be assumed is the one comprising conductors 485-487, inclusive. When this idle trunk is reached, switching relay 465, being no longer short circuited, energizes in series with stepping relay 464, but stepping relay 464 does not energize at this time on account of the high resistance of 125 switching relay 465. Upon energizing, switching relay 465 opens the test circuit and prepares the holding circuit at armature 473; removes ground from armature 466 of line relay 461 at armature 474, thereby opening 130

the circuit of the slow acting release relay 462; and at armatures 472 and 475 disconnects conductors 445 and 448 from line relay 461 and extends them by way of wipers 482 and 484 and conductors 485 and 487 to the upper and lower windings of the double wound line relay 501 of the repeater R through the upper and lower left hand windings of the associated repeating coil. Relay 501 now energizes over the outgoing control circuit of the director and closes at armature 503 a circuit for release relay 502 which thereupon energizes and places ground upon release trunk conductor 486 at armature 505, thereby closing the usual holding circuit for switching relay 465 of the selector S before the slow acting release relay 462 has had time to deenergize.

In the repeater R, as a further result of the energization of line relay 501, it closes a bridge across the associated inter-office conductors leading to the selector S¹³ in Cedar at armature 504, whereupon the selector S¹³ is prepared for operation in the usual manner. In the director, the slow acting pick-up relay 815, Fig. 8, deenergizes after the interval for which it is adjusted and opens the circuit of stop relay 816 and of stepping magnet 720 of the sequence switch S', Fig. 7, at armature 855, and at armature 854 places another shunt around the sending contacts 813. Stepping magnet 720 now deenergizes and advances the sequence switch wipers 722-724, inclusive, into engagement with the second set of bank contacts, and stop conductor control wiper 724 removes ground from the first code digit stop conductor 761 and places ground on the second code digit stop conductor 762 preparatory to the transmission of the second digit in the desired number. This later operation does not have any particular utility at this moment for the reason that the second digit, being 0, does not require a jumper to be run on the intermediate distributing frame IDF. Accordingly, the bank contact 962 with which the second wiper of the office register 942 is now in engagement is not connected up on the intermediate distributing frame.

After the interval for which it is adjusted the slow acting stop relay 816 of the sender also deenergizes and again connects up the stepping magnet 817 to the start circuit at armature 859, thereby initiating the transmission of the second digit 0. As pointed out above, none of the impulse stop conductors are grounded at this time, and the counting switch CS continues to advance and the stop relay 816 is not energized until the last contact in the bank of wiper 820 is reached, which contact is grounded locally. The stop relay 816 then energizes with the result that the digit being transmitted is terminated in the same manner as pointed out in connection with the first code digit 3.

Responsive to the transmission of the second code digit 0 the line relay 501 of the repeater R, Fig. 5, deenergizes ten times momentarily and, upon each deenergization, opens the bridge across the associated inter-office trunk conductors at armature 504, with the result that the selector S¹³ in Cedar is operated in the well known manner to raise its wipers opposite the tenth level of bank contacts and select an idle trunk, which trunk, it will be assumed, is the one extending to the repeater R⁹. Accordingly, the repeater R⁹ operates in the same manner as the repeater R and prepares the distant selector S²¹ in Edgewater for operation in the usual manner.

In the director, the sequence switch S' is advanced another step in the hereinbefore described manner, and wiper 724 grounds the third code digit stop conductor 763 preparatory to terminating the third code digit 6.

The sending operation is again started in the usual manner and continues until stop relay 816 is energized at the end of the sixth interruption of the outgoing control circuit. The circuit of stop relay 816 at this time is as follows: From ground by way of the grounded stop conductor control wiper 724 of the sequence switch S', the third associated bank contact, the third code digit stop conductor 763, the third wiper 943 of the office register OR, bank contact 963, jumper 972 on the intermediate distributing frame IDF, the sixth impulse stop conductor 956, the corresponding contact in the bank of wiper 820 of the counting switch CS, wiper 820, and stop relay 816 to battery.

In the office Edgewater, the selector S²¹ raises its wipers opposite the sixth level responsive to the transmission of the third code digit 6 and selects an idle trunk, which trunk, it will be assumed, is the one extending to the repeater R¹⁵. Accordingly, the repeater R¹⁵ operates in the same manner as described for the repeater R and causes the distant selector S³³ in Main to be prepared for operation in the usual manner.

The sequence switch S' of the director is again advanced after the third digit and wiper 724 grounds the fourth code digit stop conductor 764. When this occurs, relay 901, Fig. 9, energizes over conductor 764 and through wiper 944 of the office register OR, bank contact 964, jumper 973, and the normally closed contacts controlled by armature 914. Upon energizing, relay 901 closes a locking circuit for itself and opens its initial circuit at armature 914, and at armature 915 connects the jumper 973 to another terminal on the intermediate distributing frame so that in case the digit to be transmitted is anything other than 0 a conductor can be run to the correct impulse stop conductor to terminate such digit. As a further result of the energization of relay 901, the second subscriber digit stop conductor 772 is discon-

5 nected from the associated conductor 772' and is connected instead to the switching conductor 731 so as to cause the switching relay to be operated when the sequence switch S' is ad-
 10 vanced after one subscriber digit has been transmitted. It will be understood, of course, that the term code digit is used herein to indicate any digit transmitted under the control of the office register OR, and that the term subscriber digit is used to indicate any digit registered upon and subsequently retransmitted under the control of one of the digit registers DR¹-DR⁴, inclusive.

15 The fourth code digit being 0 does not re-
 20 quire any jumper on the intermediate distributing frame IDF and is terminated in the usual manner when the stop wiper 820 of the counting switch CS engages its last bank contacts.

25 Responsive to the transmission of the fourth code digit 0, the selector S³² in Main raises its wipers opposite the tenth level of bank contacts and selects an idle trunk, which trunk, it will be assumed is the one extending to the selector S³⁶. That being the case, the selector S³⁶ is prepared for operation in the usual manner.

30 In the director, the sequence switch S' is advanced in the usual manner after the transmission of the fourth code digit 0, and the stop conductor control wiper 724 grounds the first subscriber digit stop conductor 771 preparatory to the termination of the first subscriber digit. Wiper 722 at this time 35 moves out of engagement with its fourth contact and into engagement with its fifth contact, thereby opening the circuit through which ground was initially supplied to the starting conductor 738 and placing ground on start conductor 738 through a new path which includes the resting contact and armature 713 of the slow acting series relay 712, conductor 743 and off normal contacts 1001 of the digit register DR¹. This circuit is 40 taken through the contacts of the slow acting relay 712 and through the off normal contacts 1001 to insure that the sender is not started to transmit the first subscriber digit before such digit is completely registered. How-
 45 ever, assuming that the first subscriber digit 1 in the desired number is registered before the last code digit is transmitted, there is no break in the start circuit following the transmission of the last code digit and the sender 50 is again started after the usual interval occasioned by the slow acting relays 815 and 816.

55 It will be remembered that the digit register DR¹ responded to the digit 1. Accordingly, this digit 1 is now retransmitted and 60 at the end of one interruption in the outgoing control circuit the wiper 820 of the counting switch CS finds ground on the third associated bank contact, thereby closing the following circuit for stop relay 816: From 65 ground by way of the stop conductor con-

trol wiper 724 of the sequence switch S', the first subscriber digit stop conductor 771, wiper 1005 of the digit register DR¹, the first associated bank contact, the first impulse stop conductor 951, the corresponding contact in 70 the bank of wiper 820, wiper 820, and stop relay 816 to battery. This energization of stop relay 816 results in the digit 1 being terminated in the hereinbefore described manner.

75 Responsive to the transmission of the digit 1, the selector S³⁶ in Main, Fig. 5, raises its wipers opposite the first level and selects an idle trunk, which trunk, it will be assumed, is the one extending to the repeater R²⁵. Accordingly, the repeater R²⁵ operates in the same manner described for the repeater R, with the result that a bridge is closed across the associated inter-office trunk conductors 601 and 602. Responsive to the closure of 80 this bridge, line relay 603 of the cord circuit CC energizes and closes at armature 604 a circuit through armature 608 and its resting contact, and the resting contact and armature 610 for the lamp 611 which, accordingly, becomes lighted to inform the operator that a 85 call has come in over the associated trunk line.

90 In the director, the wipers of the sequence switch S' are again advanced in the usual manner subsequent to the termination of the digit 1, and wiper 724 places ground upon the second subscriber digit stop conductor 772 preparatory to terminating the second subscriber digit in case one is registered.

95 At this time, however, the registered number contains only one subscriber digit and relay 901 is energized as hereinbefore pointed out. Accordingly, the placing of ground upon conductor 772 results in a circuit being closed for switching relay 815 as follows: 100 From ground by way of the grounded wiper 724 of the sequence switch S', conductor 772, armature 913 of relay 901 and its working contact, switching conductor 731, normally closed contacts controlled by armature 853, 105 and switching relay 814 to battery. Switching relay 814, upon energizing, closes a locking circuit for itself and opens its initial circuit at armature 853; disconnects the timing conductor 804 from relay 808 at armature 852; opens the starting circuit at armature 851; and at armature 850 disconnects the combined switching and operating conductor 452 from the operating conductor 725 110 and connects it to ground, resulting in the energization of switching relay 423 of the trunk circuit TC over the hereinbefore traced path.

115 Accordingly, switching relay 423 switches the connection through and cuts off the line relay 421, whereupon the line relay 120 of the repeater R, Fig. 5, is maintained energized under the direct control of the calling line. The release relay 422 of the trunk circuit TC deenergizes after an interval and 125 opens the circuit of switching relay 435 of the 130

director selector DS, whereupon switching relay 435 deenergizes and frees the director, removing ground from the release trunk conductor 451 at armature 438.

- 5 In the director, responsive to the removal of the ground potential from release trunk conductor 451 at the director selector DS, relay 809, which has heretofore been shortcircuited, now energizes over the following circuit: 10 from ground by way of the off normal contact 714 of the sequence switch S, conductor 729, relay 809, armature 832 and its resting contact, and relay 806 to battery. Accordingly, relay 806 is maintained energized as are the 15 relays 814 and 901 which are now locked up to the release trunk conductor 451. It may be pointed out that the resistance of relay 809 is low enough to enable the ground potential placed upon conductor 751 through the 20 winding of the said relay 809 to make the director busy to any director selector that might happen to be testing at this time. It may be pointed out also, that at no time is the director left unguarded until all the apparatus in the 25 director is restored to normal as will now be pointed out.

Upon the energization of relay 809, ground is placed upon release conductor 743 through the low wound relay 805 thereby closing a circuit through off normal contacts 1002 for the release magnet 1003 of the digit register DR¹, Fig. 10, another circuit through off normal contacts 912 for the release magnet 911 of the office register OR, and still another circuit 30 through off normal contact 715 for the release magnet 716 of the sequence switch S', Fig. 7. Relay 805 energizes in series with the above named release magnets and places ground directly upon the release trunk conductor 451 at armature 732, at the same time disconnecting release relay 806. Release relay 806 now deenergizes and stops the interrupter 811 at armature 837. Release relay 806 also disconnects the bank of wiper 819 of 35 the counting switch CS from ground at the working contact of armature 836 and connects it to ground through the guard relay 805. As a further result of the deenergization of release relay 806, it places a shunt 40 around armature 848 and its working contact of relay 809 at armature 835 so as to take over the function of armature 848; closes the normal restoring circuit of the counting switch CS at armature 833 which is effective only in 45 case the director is freed while the counting switch CS is off normal; and at armature 834 completes the normal restoring circuit of the sequence switch S' over conductor 730.

Responsive to the closure of the circuits of 50 the release magnet of the digit register DR¹, the office register OR, and the sequence switch S, the associated switches are restored to normal position in the usual manner, and the circuit of each release magnet is opened at its 55 respective associated off normal contacts.

Responsive to the closure of the normal restoring circuit of the sequence switch S' the self interrupting stepping magnet 720 is operated through the interrupter contacts 721 and wiper 723 and its associated bank of 70 contacts and advances the associated wipers step by step until the wipers are advanced to their normal position at which point the circuit of the stepping magnet 720 is open on account of wiper 723 passing off the last bank 75 contact.

When all the switches of the director have been restored to normal, the guard relay 805 deenergizes and disconnects ground from the release trunk conductor 451 at armature 832, 80 whereupon relay 901, Fig. 9, and switching relay 815, Fig. 8, deenergize because ground is no longer supplied to release trunk conductor 451 through relay 809 on account of the fact that the off normal contacts 714 of 85 the sequence switch S are now open. The director is now free to be seized to handle another call.

Returning now to the point at which the lamp 611 of the cord circuit CC, Fig. 6, became lighted, the operator upon noting the lighted condition of the lamp throws her listening key K and gets into communication with the calling subscriber. The key K, upon being operated, closes a circuit for relay 604 95 which energizes and closes a locking circuit for itself at armature 609, and at armature 608 opens the circuit of the lamp 611. Upon being informed of the number of the desired subscriber, the operator inserts the plug of the 100 cord circuit CC into the jack J after which she operates her ringing key K' to signal the desired subscriber.

When the called subscriber responds by removing his receiver the conversation may 105 proceed.

When the conversation is terminated, the two subscribers replace their receivers. When the receiver is replaced at substation A, line relay 603 of the cord circuit CC, Fig. 6, deenergizes and completes at armature 606 a disconnect circuit for the lamp 611 through the working contact and armature 610 of the sleeve relay 605. Upon noting the lighted condition of the lamp 611 the operator withdraws the plug of the cord circuit CC from the jack J. 110

In the originating exchange, upon the deenergization of the slow acting release relay 502 of the repeater R, Fig. 5, ground is 115 removed from the release trunk conductor 486, whereupon the switching relay 465 of the selector S, the switching relay 423 of the trunk circuit TC, and the switching relay 404 of the line switch LS deenergize. Upon the 120 deenergization of switching relay 465 of the selector S a circuit is closed at armature 474 for release magnet 479 through armature 436 and its resting contact, armature 468 and its 125 resting contact, and the off normal contacts 130

478. Release magnet 479 now energizes and restores the selector S to normal position in the usual manner, the circuit of release magnet 479 being opened at off normal contacts 5 478 when the normal position is reached. The other switches involved in the connection are released in substantially the same manner as the selector S.

In order to explain how calls originating 10 in Meadow and intended for main office subscribers are handled, it will be assumed that the subscriber at substation A desires to call a subscriber whose line terminates in one of the main offices of the system, for example 15 the office Main. In order to make the example still more concrete it will be assumed that the called subscriber is the subscriber at substation A³, Fig. 3. This substation is not shown in the circuit drawings, but the major 20 part of the switches necessary in establishing the connection are shown in Figs. 4 and 5. Accordingly, it is not thought necessary to further complicate the drawings to show the remaining part of the switches and the 25 called substation as the invention more particularly concerns the arrangement in the originating office. It will be assumed further that, when the subscriber at substation A removes his receiver, the line switch LS 30 selects the trunk circuit TC and that the director selector DS selects the director shown in the drawings. Accordingly, the director is prepared for operation in the hereinbefore described manner.

35 When the calling subscriber at substation A manipulates his calling device in accordance with the first digit 6, in the desired number, the office register OR, Fig. 9, raises its wipers opposite the sixth level of bank contacts in the manner hereinbefore described, and when the second digit 1 is called the wipers of the office register are rotated into engagement with the first set of bank contacts (not shown) in the first level. At the end 40 of the rotary movement the sending operation is started upon wiper 718 of the sequence switch S coming into engagement with its third bank contact as it does in the previously described manner.

45 It will be appreciated at once that since the call previously described was trunked to the desired manual office through the main office, the present call must follow the same route as far as the main office. Accordingly, the director must in this case, as before, send out the code digits 3, 0 and 6, but since the second digit in the called number is 1 in this case, as compared with 0 in the previous case, the fourth code digit to be transmitted in this 50 case is the code digit 1. Accordingly, the contact in the set of bank contacts of the office register OR now in use, and corresponding to the bank contact 964 of the set shown, is cross connected to the first impulse stop 55 conductor 951 on the opposite side of the in-

termediate distributing frame IDF, thereby predetermining that the fourth code digit to be transmitted is the code digit 1. It may be pointed out, at this time, that since three subscriber digits are to be transmitted by the director instead of one as in the previous case, it is unnecessary to operate any relay corresponding to the relay 901 which was operated in the previous case in order to permit the director to cut off and free itself following the transmission of one subscriber digit.

At the end of the transmission of the first three code digits 3, 0 and 6, the wipers of the sequence switch S' are advanced another step in the usual manner and wiper 724 places 80 ground upon the fourth code digit stop conductor 764 preparatory to the termination of the fourth code digit.

When the sender is again started for the fourth code digit, it transmits one impulse in 85 the usual manner after which the stop relay 816 is energized over the following circuit: From ground by way of the stop conductor control wiper 724 of the sequence switch S', the fourth code digit stop conductor 764, the 90 fourth wiper 944 of the office register OR, the bank contact (not shown) with which it is in engagement, the associated jumper on the intermediate distributing frame IDF also not shown, the first impulse stop conductor 951, 95 the corresponding contact in the bank of the counting switch CS, wiper 820, and stop relay 816 to battery. The counting switch CS is now restored to normal in the usual manner and the sequence switch S' again advances its wipers one step and wiper 724 grounds the first subscriber digit stop conductor 771.

It may be assumed that in the meantime the calling subscriber has dialled the three subscriber digits 1, 0 and 0, and that these digits have been registered on the digit registers DR¹, DR² and DR³, respectively. The first of these three digits is transmitted in the same manner as the corresponding subscriber 105 digit 1 in the number of the subscriber at substation A⁴, previously considered. At the end of the transmission of this subscriber digit 1, the counting switch is restored to normal and the sequence switch S' is again advanced one step and the start conductor control wiper 722 places ground upon conductor 744, thereby extending ground to the start conductor 738 through the upper off normal contacts of the digit register DR³ in case this 110 register has been operated, as hereinbefore assumed. Accordingly, the sender is started to transmit the second subscriber digit 0 and it continues to advance until ten impulses have been transmitted, owing to the fact that 115 the wiper of the digit register DR² has been advanced to the last contact and does not close a circuit for the stop relay through any of the nine impulse stop conductors. The stop relay 816 is operated in the usual manner when 120 125 130

the normally grounded contact is reached after the tenth interruption has been produced in the outgoing control circuit.

After having been again restored to normal, the counting switch CS is again started for the third and last subscriber digit 0 responsive to start conductor 738 being grounded by the start conductor control wiper 720 of the sequence switch S' through seventh 5 associated bank contact, resting contact and armature 709, conductor 744, and the upper off normal contacts of the digit register DR³. This digit being 0 is terminated in the same manner as the previous digit 0, the wiper of 10 this digit register also having been advanced to the last contact.

The wipers of the counting switch CS are again restored to normal position in the usual manner, and the sequence switch S^s is advanced one step whereupon the stop conductor control wiper 724 places ground upon the fourth subscriber digit stop conductor 774. In this case there is no fourth subscriber digit 20 to be transmitted and the director is ready to be freed. Accordingly, a circuit is closed over conductor 774, conductor 737, armature 711 and its resting contact, conductor 731, normally closed contacts controlled by armature 853, and switching relay 814 to battery. 25 Upon the closure of this circuit switching relay 814 energizes with the result that the switching relay of the trunk circuit TC is operated with the hereinbefore described results and the director is freed in the usual manner.

The effect of the transmission of the digits by the director will now be considered. In response to the transmission of the first three code digits 3, 0 and 6, it may be assumed that 30 the call was extended over the same path as in the previous case when the code digits 3, 0 and 6 were transmitted, namely, through the selector S, the repeater R, the selector S^{13} , the repeater R⁰, the selector S²¹, and the repeater R¹⁵ to the selector S³³ in Main, Fig. 5. Accordingly, responsive to the transmission of 35 the fourth code digit 1, the selector S³³, Fig. 5, raises its wipers opposite the first level and selects an idle trunk, which trunk, it may be assumed, is the one extending to the selector S³⁵ which is shown in the trunking diagram of Fig. 3. Accordingly, upon the transmission of the first subscriber digit 1 the selector S³⁵ raises its wipers opposite the first level and 40 selects an idle trunk, which, it may be assumed, is the one extending to the connector C³. That being the case the connector C³ responds to the last two digits 0 and 0 to raise its wipers opposite the tenth level of bank 45 contacts and to bring them into engagement with the tenth set of contacts in that level, thereby completing the connection to the called line in the usual manner. The remaining part of the operation being old need not be considered here.

In order to explain another part of the operation it will be assumed that the subscriber at substation A desires to set up a long distance connection. Accordingly, the first step is to remove his receiver and dial 70 the digit 0 so as to get into communication with the toll recording operator. It will be assumed that when he removes his receiver the line switch LS selects the trunk circuit TC and that the director selector DS selects 75 the director shown in the drawings. Accordingly, when the digit 0 is dialled the office register OR, Fig. 9, raises its wipers opposite the tenth level of bank contacts in the usual manner. When the tenth level is 80 reached the tenth level shaft springs are operated, and contacts 904 are opened and contacts 905 are closed. The contacts 904 are for the purpose of opening the impulsing circuit so as to prevent any further operations of the 85 calling subscriber's calling device that might take place from having any further effect in the director. The contacts 904 are opened just before the last vertical step is completed. This does not cause any harm to result, however, owing to the fact that the contacts 904 are, at that instant, shunted by armature 797 of the series relay 702.

When the series relay 702 subsequently falls back it opens the impulse circuit at armature 95 797, and at armature 706 closes the usual circuit for stepping magnet 717 of the sequence switch S through the working contact and armature 705, and, since the tenth level contacts 905 are closed, a circuit is closed over 100 conductor 735 and through the said contacts 905 for the rotary magnet 910 of the office register OR by way of conductor 734, armature 704 and its working contact, and conductor 742. Accordingly, rotary magnet 910 105 is automatically operated to advance the wipers of the office register into engagement with the first set of bank contacts, not shown, in the tenth level.

After a slight interval the slow acting relay 110 701, Fig. 7, deenergizes and at armature 704 opens the circuit of the rotary magnet of the office register and places ground upon the start conductor control wiper 722 of the sequence switch S' and the stop conductor control wiper 724, thereby starting the counting switch CS over the usual circuit. Since the toll recording operator is to be reached by way of the office Edgewater, and is located in the center office, as is indicated in Fig. 3, it 115 is necessary for the director to transmit the digits 3 and 0 to trunk the call to Edgewater and to transmit the digit 0 to operate the selector S²¹ to seize a toll recording trunk to center. Accordingly, the first contact in the 120 set of bank contacts engaged by the wipers of the office register OR at this time is cross connected by means of a jumper to the third impulse stop conductor 953, thereby predetermining that the first code digit to be trans- 125 130

mitted is the code digit 3. The second and third contacts in the set in use are not cross connected at all on account of the fact that the corresponding digits are 0 in both cases.

5 In order to enable the director to "switch" at the end of the third code digit 0, the fourth contact or the one engaged by the fourth wiper 944 of the office register OR is cross connected by means of a jumper on the intermediate distributing frame IDF to the switching conductor 731. Accordingly, after the three code digits have been transmitted in the usual manner, the switching relay 814, Fig. 8, is energized over the following circuit: from ground by way of the grounded stop conductor control wiper 724 of the sequence switch S', the fourth code digit stop conductor 764, wiper 944 of the office register OR, the bank contact with which it is in engagement, the corresponding jumper, not shown, conductor 731, normally closed contacts controlled by armature 853, and switching relay 814 to battery. Responsive to the energization of switching relay 814 the connection is switched through and the director is freed in the usual manner.

It will be understood that responsive to the first two code digits 3 and 9 the call is trunked to Edgewater in the usual manner, and that responsive to the third code digit 0 the selector S²¹ (assuming that this is the selector seized when the call is trunked to Edgewater) raises its wipers opposite the tenth level and selects an idle trunk, for example the trunk extending to the repeater R¹¹, Fig. 3. The remaining part of the operation, being old, need not be considered here.

In order to explain a further feature of the invention it will be assumed that the subscriber at substation A desires to call a subscriber whose line terminates in Cedar. It will be assumed further that the called subscriber is the subscriber at substation A', Fig. 2, and whose number is 301100.

45 When the calling subscriber dials the first digit 3, the office register OR raises its wipers opposite the third level of bank contacts and when the calling subscriber dials the second digit 0 the wipers are rotated into engagement with the tenth set of bank contacts in the selected level. In this case it is desired to omit all code digits and to transmit four subscriber digits. Accordingly, arrangements have been made for operating the relay 50 705 so as to enable the desired results to be accomplished. When the wipers of the office register are advanced the tenth step, the tenth rotary step contacts 745 are closed by the cam 746 controlled by the shaft of the office register, thereby energizing relay 703 with results which will be understood upon a further perusal of the description.

At the end of the rotary movement of the office register OR the wipers 718 and 719 of the sequence switch S are advanced another

step in the usual manner and wiper 718 grounds the control wipers 722 and 724 of the sequence switch S'. The grounding of the start conductor control wiper 722, however, does not result in the starting of the counting switch CS, as is ordinarily the case, owing to the fact that relay 703 is now energized and the start circuit is open at armature 708. The grounding of the stop conductor control wiper 724, however, results in the first code digit stop conductor 761 being grounded. Since no code digits are to be transmitted, all four bank contacts now engaged by the wipers of the office register are cross connected on the intermediate distributing frame IDF to the skip conductor 732. Accordingly, upon the first code digit stop conductor 761 being grounded, a circuit is closed through wiper 941 of the office register OR, the bank contact with which it is in engagement, (not shown), the corresponding jumper on the intermediate distributing frame IDF, (also not shown), skip conductor 732, interrupter contacts 721 of the sequence switch S', and magnet 720 to battery. Stepping magnet 720, accordingly, energizes preparatory to advancing the wipers and opens its circuit at contacts 721, whereupon it deenergizes advancing the wipers one step. Since each of the three remaining bank contacts in the set in use of the office register OR are cross connected to the skip conductor in the same way, the sequence switch S' takes three more steps and automatically advances until its wipers arrive upon the fifth set of bank contacts.

As soon as the calling subscriber has dialled the first digit 1 and as soon thereafter as the slow acting series relay 712, Fig. 7, which is in series with the stepping magnet 104 of digit register DR¹ has deenergized, the usual starting circuit for the counting switch CS for sending out the first subscriber digit is closed and the first subscriber digit 1 is transmitted in the usual manner.

As soon as the calling subscriber has dialled the second and third digits 1 and 0 in the desired number, the usual starting circuit is closed for transmitting the second digit, whereupon the second digit 1 registered upon the second digit register DR² is transmitted in the usual manner and is terminated upon the energization of stop relay 816 over the following circuit: from ground by way of the grounded stop conductor control wiper 724 of the sequence switch S', the second subscriber digit stop conductor 772, the wipers of the digit register DR², the first associated bank contact, the first impulse stop conductor 751, and thence to battery over the previously traced circuit by way of wiper 820 and stop relay 816.

The energization of stop relay 16 at this time results in the digit being terminated in the usual manner and in the sequence switch S' being advanced another step. In

this case, the counting switch CS is not started for the third subscriber digit through the off normal contacts of the third digit register DR³ owing to the fact that conductors 5 744 and 745 are disconnected from each other at this time at armature 709 of relay 703. Accordingly, the counting switch CS is not started to transmit the third subscriber digit 10 0 until the fourth digit register DR⁴ has moved off normal, at which time the counting switch CS is started over the following circuit: from ground by way of the start conductor control wiper 722 of the sequence switch S', conductor 745, the upper pair of off 15 normal contacts of the digit register DR⁴, and thence by way of start conductor 738 to battery over the usual circuit.

The sequence switch S' is advanced in the usual manner one step after the transmission 20 of the third subscriber digit 0. The starting circuit for starting the counting switch CS for the transmission of the fourth subscriber digit 0 is the same as the starting circuit over which it was started for transmitting the preceding digit, the seventh and 25 eighth contacts in the bank of wiper 722 of the sequence switch S' being tied together as shown, owing to the fact that the wiper of the digit register DR⁴ has been advanced 30 to its tenth position and is in engagement with a dead contact, the stop relay 816 is not energized until the counting switch CS has counted off ten impulses at which time it energizes from the locally grounded contact, terminating the fourth subscriber digit in the 35 usual manner.

After the usual slight interval, the wipers of the sequence switch S' are again advanced one step and the stop conductor control wiper 40 724 places ground upon the switching conductor 731 upon coming into engagement with its ninth associated bank contact, thereby closing a circuit over switching conductor 731 for the switching relay 814, resulting 45 in the switching relay of the trunk circuit TC, Fig. 4, being operated in the usual manner and the director being freed.

The effect of the transmission of the subscriber digits 1, 1, 0, and 0 will now be considered. Responsive to the transmission of 50 the first subscriber digit 1, the selector S, Fig. 4, raises its wipers opposite the first level and selects an idle trunk, which trunk, it will be assumed, is the one extending to the repeater R⁴ (not shown in the circuit drawing), Fig. 2. Accordingly, the distant associated selector S¹¹ in Cedar is prepared for operation 55 in the usual manner and, responsive to the second subscriber digit 1, the selector S¹¹ raises its wipers opposite the first level of 60 bank contacts and selects an idle trunk, for example, the trunk extending to the connector C'. That being the case, the connector C' responds to the last two digits 0 and 0 65 and raises its wipers opposite the tenth level

of bank contacts and then rotates them into engagement with the tenth set of contacts in the tenth level to complete the connection through the line of substation A'.

The remaining part of the operation, being 70 old, need not be considered herein.

In order to explain still another feature, it will be assumed that a calling subscriber, for example, the subscriber at substation A, in making a call, inadvertently operates his calling device in accordance with a dead number or a number which has yet been assigned. For example, there are no numbers beginning with the digit 1. Accordingly, each set of contacts in the first level of the bank of the office register OR is cross-connected on the intermediate distributing frame IDF in such a manner that in case the wipers of the office register land upon such bank contacts, the dead number code 61110 is transmitted to 75 stop the call to the monitoring operator in Main, Fig. 3. The way in which this is accomplished will now be pointed out. In case a calling subscriber dials the digit 1 as the first digit and follows that digit by a second 80 digit, the wipers of the office register OR, Fig. 9, are raised opposite the first level of bank contacts and are then rotated into engagement with a set of contacts in the first level. The first contact in the set with which 85 the wipers are brought into engagement is cross-connected on the intermediate distributing frame IDF to the conductor associated with the dead code relay 902. Accordingly, 90 when the stop conductor control wiper 924 of the sequence switch S' is grounded by wiper 718 of the sequence switch S at the end 95 of the second digit, a circuit is closed for relay 902 as follows: from ground by way of the grounded wiper 724, the first code digit 100 stop conductor 761, the first wiper 941 of the office register OR, the bank contact with which it is in engagement, the associated jumper (not shown), conductor 983, normally 105 closed contacts controlled by armature 918 and relay 902 to battery. Relay 902 energizes 110 over this circuit and closes a locking circuit for itself at armature 918 at the same time opening its initial circuit, and at armature 919 connects conductor 982 to conductor 983. 115 As a further result of the energization of relay 902, it opens the impulse circuit at armature 916 so as to render any further operation 120 of the calling subscriber's calling device ineffective in operating any of the digit registers DR¹-DR⁴, inclusive, and at armature 917 places ground upon the start conductor 738 so as to maintain the said start conductor grounded after the start conductor control wiper 722 of the sequence switch S' 125 has advanced off the fourth contact at the end of the transmission of the fourth code digit, as it will subsequently.

The contact upon which wiper 941 of the office register OR is standing is now con- 130

connected through conductor 982, working contact and armature 919, conductor 983, and jumper 984 to the third impulse stop conductor 953. Accordingly, the first code digit 5 3 is transmitted in the usual manner and is terminated upon the energization of stop relay 816 through wiper 820 and over the third impulse stop conductor 953.

The bank contact upon which the wiper 10 942 is standing is left dead; the bank contact upon which the third wiper 944 of the office register OR is standing is cross-connected to the sixth impulse stop conductor 956; and the fourth wiper 944 of the office register OR 15 is cross-connected to the first impulse stop conductor 951. Accordingly, the code digits 3, 0, 6, and 1 are transmitted under the control of the office register OR at the end of which the sequence switch S' advances its wipers 20 into engagement with the tenth set of bank contacts. The first, second, and third subscriber digit stop conductors are now connected to the working contact and armatures 920, 921, and 922, respectively, to contacts on 25 the intermediate distributing frame. The jumper 979 connects the first subscriber digit stop conductor to the first impulse stop conductor 951; the second subscriber digit stop conductor is connected by means of the jumper 30 980 to the first impulse stop conductor 951 also; and the jumper 981 connects the third subscriber digit stop conductor to the ninth impulse stop conductor 959. Accordingly, the three remaining code digits 1, 1, and 9 35 are transmitted following which the wipers of the sequence switch S' are advanced into engagement with the seventh set of bank contacts and a circuit is closed for switching relay 814, Fig. 8, as follows: from ground 40 by way of the grounded stop conductor control wiper 724 of the sequence switch S', conductor 774, conductor 737, armature 711 and its resting contact, switching conductor 731, and thence to battery through the normally 45 closed contacts controlled by armature 853 and switching relay 814. Upon the energization of switching relay 814, the switching relay of the trunk circuit TC is operated and the director is freed in the usual manner.

50 The effect of the transmission of the code number 3031119 will now be considered. It may be readily assumed that the call is trunked to the connector C³, Fig. 3, in Main responsive to the transmission of the digits 55 3, 0, 6, 1, and 1 in the same manner as was pointed out in connection with the call to the subscriber at substation A³. Accordingly, responsive to the transmission of the last two digits 1 and 9, the connector C³ raises its 60 wipers opposite the first level and then rotates them into engagement with the ninth set of bank contacts in the first level, extending the connection to the monitoring operator, who, if desired, may be provided with 65 an ordinary substation set to answer the call.

The operator will know from the line over which the call comes to her that it is a dead number call.

In order to describe still another operation, it will be assumed that the subscriber at 70 substation A has removed his receiver to make a call and that the line switch LS has seized the trunk circuit TC and the director selector DS has seized the director shown in the drawing. It will be assumed further that 75 the calling subscriber has called the first two digits of the desired number but has not finished dialling the number and that he waits over the maximum time allowed by the timing arrangement for the director before dialling the remaining part of the number.

It will be recalled that the timing conductor 804, Fig. 8, is connected up to the upper winding of the two-step relay 808 by the release relay 806 upon the director being seized 80 and that the two-step relay 808 operates through its first step upon its circuit being closed by the slow interrupter and operates through its upper step upon its circuit being opened by the said slow interrupter. It may 85 be recalled also that the locking circuit of the two-step relay 808 through which the lower winding of the relay is energized and causes the relay to operate through its second step, includes the armature 706 of the series relay 90 702 and conductor 860. Accordingly, each time a digit is dialled by the calling subscriber, the locking circuit of the two-step relay 808 is opened at armature 706 so as to cause the timing operation to start anew after 95 the dialling of each digit. It will be at once appreciated that when the calling subscriber continues to dial the digits one right after another, there is no chance for the timing operation to be completed before the complete number is dialled and retransmitted. On 100 the other hand, if, according to the foregoing assumption, the calling subscriber waits between the dialling of two digits until the conductor 804 is again grounded after relay 105 808 has become locked up, a circuit is completed for relay 807, Fig. 8, as follows: from ground by way of the contacts of the slow interrupter 803, Fig. 8, the common timing conductor 804, armature 839 and its working 110 contact, resting contact and armature 852, armature 847 and its working contact, normally closed contacts controlled by armature 845, conductor 862, off normal contacts 907 of the office register OR, Fig. 9, and its upper 115 contact, conductor 861 and relay 807 to battery. Relay 807 energizes when this circuit is closed upon the closure of the contacts of the interrupter 803; opens its initial circuit and completes a locking circuit for itself independent of off normal springs 907 of the office register at armature 845; places a shunt 120 around armature 832 and its resting contact of relay 805 at armature 844 so as to prevent the release relay 806 from being disconnected 125 130.

nected from the release trunk conductor 451 upon the energization of relay 805 which is to occur shortly; and at armature 840 disconnects ground from armature 727 so as to 5 remove ground from the start conductor 738 to stop the operation of the counting switch CS in case it is operating at this time and places ground upon the conductor 728 thereby closing a circuit for relay 903. Relay 903 10 now energizes and closes a locking circuit for itself at armature 925, and at armatures 926-932, inclusive, connects the four code digit stop conductors 761-764, inclusive, and the first three subscriber digit stop conductors 15 771-773, inclusive, respectively, to the intermediate distributing frame preparatory to sending out the delayed call number 3061110.

As a further result of the energization of relay 807, Fig. 8, it opens the outgoing control circuit at armature 841 so as to release the partly established connection that may be set up; places ground through the low wound relay 805 upon the release conductor 743 at armature 842, thereby releasing the office 20 register OR and any one of the digit registers DR¹-DR⁴, inclusive, that may happen to be off normal at this time; and at armature 843 places ground upon the restoring conductor 730 of the sequence switch S', thereby 25 restoring the sequence switch S' to normal position in the usual manner. It may be pointed out that it is unnecessary to provide any contact on the relay 807 for restoring the counting switch CS to normal position for 30 two reasons. The first reason is that it is impossible for the counting switch CS to be off normal at this time in case all the circuits are functioning properly because of the fact that the interval of time required for the timing 35 apparatus to operate to energize relay 807 is sufficiently long to permit any registered digit to be transmitted and to permit the counting switch CS to be restored to normal position in the usual manner. The second reason is that in case the counting switch CS happens 40 to be off normal at this time, due possibly to some temporary circuit defect, it is restored to normal position responsive to the closure of its restoring circuit at armature 857 of stop relay 816 which energizes in multiple with 45 stepping magnet 720 of the sequence switch S^s as the latter is being operated to restore the sequence switch S' to normal position.

When ground is subsequently removed 50 from the timing conductor 804, relay 807 de-energizes and replaces ground upon conductor 727 at armature 840, whereupon ground is extended through the working contact and armature 924 of relay 903, Fig. 9, to the start conductor 738, thereby starting the counting switch CS for the first code digit.

The first code digit stop conductor 761 is connected through armature 926 of relay 903 and the jumper 974 to the third impulse stop 55 conductor 953; the second code digit stop

conductor 762 is connected through armature 927 to the intermediate distributing frame IDF but is there left dead; the third code digit stop conductor 763 is connected through armature 928 and the jumper 975 to the sixth 70 impulse stop conductor 956; and the fourth code digit stop conductor 764 is connected through armature 929 to the intermediate distributing frame and is connected by the jumper 984 to the first impulse stop conductor 951. 75 Accordingly, the code digits 3, 0, 6 and 1 are transmitted by the sender. The first subscriber digit 771 is connected through armature 920 and jumper 976 to the first impulse stop conductor 951; the second subscriber 80 digit stop conductor 772 is connected to armature 931 and the jumper 977 also to the first impulse stop conductor 951; and the third subscriber digit stop conductor 773 is connected through armature 932 to the intermediate distributing frame but is there left dead. 85 Accordingly, the three subscriber digits 1, 1 and 0 of the number are transmitted in the usual manner after which the switching relay 815 energizes, with the result that the switching relay of the trunk circuit TC energizes and the director is freed in the usual manner.

The result of the transmission of the delayed call number will now be considered. 95 It will be at once apparent that since the delayed call number differs from the dead code number, as transmitted by the director, only in that the last digit is 0 instead of 9, the connector seized, responsive to the transmission of the hundreds digit 1, raises its wipers as in the previous case to the first level of bank contacts responsive to the transmission of the tens digit 1. Now when the last digit 0 is transmitted the connector in use, the connector C³ for example, Fig. 3, rotates its wipers into engagement with the tenth set of bank contacts in the first level, thereby extending the connection to the monitoring operator's position over the delayed call circuit. 100 105 110

Regarding the directors in the automatic satellite office Cedar, it may be pointed out that these directors may be identical with the ones shown in the drawings, except that the cross connecting on the intermediate distributing frame in the case of the directors in Cedar is such that on calls to and beyond Edgewater the code digit 3, which is transmitted by the directors in Meadow for the 115 purpose of trunking the calls to Cedar, is omitted, and the corresponding contact in the bank of the office register OR is cross connected to the skip conductor 732 in order to advance the sequence switch S' to the next 120 position.

Referring now to Fig. 4, it may be pointed out that in case it is desired to make the director, shown in the drawings, busy temporarily, the locking push button P may be 130

operated to disconnect the associated bank contact from the release trunk conductor 451 and connect it to ground. The key is restored again when it is desired to cut the director in service again.

The jacks J' and J^2 are provided for the purpose of enabling an attendant to test the director to see that it is working properly. When a plug is inserted into the jack J^2 the associated bank multiple is disconnected from conductors 451 and 452, and the bank multiple corresponding to the release trunk conductor 451 is grounded to make the director busy. Conductor 451 is connected, it will be noted, to the tip spring of the jack J^2 to enable the release trunk conductor 451 to be grounded in the attendant's test set, not shown. Conductor 452 is connected to the ring contact of the jack J^2 enabling the attendant to transmit impulses to the director over conductor 452 as desired. Also, the conductor 863, which is connected to the normal contacts in the bank of test wiper 819 of the counting switch CS, is connected to the sleeve of the jack J^2 so that when the attendant grounds the sleeve conductor of the jack J^2 without having operated the release relay 806, Fig. 8, the counting switch CS will operate continuously through the self interrupting contacts 818, and its speed may be better judged and regulated than if it always stopped upon reaching its normal position and had to be pushed off by hand each time it is desired to make it rotate again.

What is claimed is:

1. In a director, office and digit registers for registering called numbers, a sender controlled by said office register for transmitting a set of code digits to trunk the call to the desired office, means for starting said sender responsive to the operation of said office register, means for omitting the code digits if a local number is called, and a relay energized when said office register is set for a local number to delay the starting of said sender.

2. In a multi-office telephone system, a network comprising a plurality of main offices, direct trunks connecting each of said offices with all the other offices, another office having trunks to only one of said first mentioned offices, and means including directors in said other office whereby a subscriber in any office may be called from any point by means of the same telephone number, each of said directors comprising registering, translating, and sending equipment.

3. In a multi-office telephone system, a main office, a sub-office having trunks to said main office and comprising a block of numbers having the same initial digit as the numbers in said main office, the subscribers in said sub-office each having a single telephone number for use in local calls and in calls from the main exchange, and directors in said sub-office for enabling local calls to be

completed exclusively over local trunk lines, each director comprising means for registering and transmitting complete numbers and for translating parts of the main exchange numbers.

70

4. In a telephone system, two exchanges, a director in the first exchange for controlling the establishment of local connections and also connections to the second exchange, an office register in said director, a digit register in said director, thousands selectors in one exchange controlled in accordance with the setting of said office register, and thousands selectors in the other exchange controlled in accordance with the setting of the said digit register.

75

5. In a telephone system, two offices, a director, an office register in said director, means for setting said office register in accordance with the office designation exclusively in case a number in one office is called and for setting said register partly in accordance with the office designation and partly in accordance with a variable group designation in case a number in the other office is called, and means effective in either case for transmitting an office code derived from the complete setting of the register.

85

6. In a director for controlling automatic switches, a plural digit register comprising a single switch, means for setting the register according to a digit representing an office and for continuing the setting according to any one of several different digits representing groups in such office, and transmitting means arranged to send out an office code derived from the complete setting, the code being the same regardless of the group digit registered.

95

7. In a director for controlling automatic switches, a plural digit register comprising a single switch, means for setting the register according to a digit representing an office and for continuing the setting according to any one of several different digits representing groups in such office, transmitting means arranged to send out an office code derived from the complete setting, the code being the same regardless of the group digit registered, and means for causing said transmitting means to send out the group digit unchanged after the code is transmitted.

105

8. In a director for controlling automatic switches, a two-motion office register in said director, means for setting said register in its primary movement according to the office designation of an exchange and in its secondary movement according to any one of the several thousands digits assigned to such exchange, and transmitting means arranged to send out the same office code regardless of the value of the thousands digits registered.

110

9. In a director for controlling automatic switches, a two-motion office register in said director, means for setting said register in

125

130

- its primary movement according to the office designation of an exchange and in its secondary movement according to any one of the several thousands digits assigned to such exchange, transmitting means arranged to send out the same office code regardless of the value of the thousands digit registered, and means for causing said transmitting means to send out the thousands digit unchanged after the code is sent.
10. In a telephone system, an office, a director in said office including means for registering designations of offices and designations of groups in the offices, a second office, means whereby calls are trunked from the first office to the second office under control of said director in accordance with an office code derived from the registration of the office designation of the second office and a group designation in such office, a third office, and means whereby calls are trunked from the first office to the third office under control of said director solely in accordance with a group designation in such third office.
15. In a register sender employing a plurality of successively operated registers and sending mechanism controlled successively by the operated registers to transmit series of digit impulses, means for starting the operation of the sending mechanism following the operation of a given one of said registers, means for starting the operation of said sending mechanism following the operation of the succeeding register, and means controlled in accordance with the setting of said given one of said registers for determining which of said starting means shall initially start the operation of said sending mechanism.
20. In a multi-office telephone system employing register senders including an office register, a plurality of digit registers, and sending mechanism operated under the control of said registers successively to transmit digit impulse series, means in said register sender for operating said office register and for operating said digit registers successively following the operation of said office register to register a complete telephone number, means effective in case said office register is set into a certain position for starting the sending mechanism at the end of the said operation of the office register, a sequence switch for placing the said sending mechanism under the control of said registers successively, and means effective in case the said office register is set into another position for delaying the starting of said sending mechanism until the first of said digit registers has been operated and for advancing said sequence switch automatically and independent of any operation of said sending mechanism to remove said sending mechanism from under the control of said office register and for placing the same under the control of the first of said digit registers.
25. In a register sender comprising an office register, a plurality of digit registers, and sending mechanism operated under the control of said registers to transmit series of digit impulses, means effective in one case 70 for operating all of said registers and for retransmitting digit impulses under the control of all of said registers and effective in another case for operating a lesser number of said registers and for retransmitting digit 75 impulses in accordance with the setting of only the operated ones of said registers, and means including a mechanically-operated device on said office register operated responsive to said office register being set in a particular position for controlling the register sender to cause it to operate properly in either of the above cases.
30. In a telephone system, a trunk line, means for extending a connection from a calling line to said trunk line automatically upon the removal of the receiver on the calling line, automatic switching mechanism for setting up a connection from said trunk line to a called line, a registering device and means for temporarily associating it with said trunk line responsive to the seizure of the latter, a magnet operating circuit extending from said trunk line to said registering device, a source of dial tone current and means for applying 85 it to the calling line by way of said magnet-operating circuit to inform the calling subscriber that he may now dial the desired number, a condenser for absorbing the induced-current surges in said operating circuit, said condenser being normally disconnected from the magnet-operating circuit, and means responsive to the operation of said registering device over the calling line for connecting 90 said condenser to said operating circuit, 100 whereby the passage of dial tone current over said operating circuit prior to the dialling of the first digit is not hindered by the said condenser.
35. In a telephone system, a switching apparatus having a test conductor, means for seizing said apparatus and for completing a guarding connection to said test conductor, means in said apparatus operative subsequent to said seizure to complete a second guarding connection to said test conductor, a relay having a winding included in said second connection and shunted by said first connection, means for releasing said apparatus after it has been operated and for energizing said relay by opening said first connection, a second relay energized responsive to the energization of the first relay, means for subsequently opening the second said connection, and contacts controlled by said second relay closed prior to the opening of said second connection for establishing a third guarding connection to said test conductor and for maintaining it until said apparatus is restored to 110 normal.
40. In a telephone system, a switching apparatus having a test conductor, means for seizing said apparatus and for completing a guarding connection to said test conductor, means in said apparatus operative subsequent to said seizure to complete a second guarding connection to said test conductor, a relay having a winding included in said second connection and shunted by said first connection, means for releasing said apparatus after it has been operated and for energizing said relay by opening said first connection, a second relay energized responsive to the energization of the first relay, means for subsequently opening the second said connection, and contacts controlled by said second relay closed prior to the opening of said second connection for establishing a third guarding connection to said test conductor and for maintaining it until said apparatus is restored to 115 normal.
45. In a telephone system, a switching apparatus having a test conductor, means for seizing said apparatus and for completing a guarding connection to said test conductor, means in said apparatus operative subsequent to said seizure to complete a second guarding connection to said test conductor, a relay having a winding included in said second connection and shunted by said first connection, means for releasing said apparatus after it has been operated and for energizing said relay by opening said first connection, a second relay energized responsive to the energization of the first relay, means for subsequently opening the second said connection, and contacts controlled by said second relay closed prior to the opening of said second connection for establishing a third guarding connection to said test conductor and for maintaining it until said apparatus is restored to 120 normal.
50. In a telephone system, a switching apparatus having a test conductor, means for seizing said apparatus and for completing a guarding connection to said test conductor, means in said apparatus operative subsequent to said seizure to complete a second guarding connection to said test conductor, a relay having a winding included in said second connection and shunted by said first connection, means for releasing said apparatus after it has been operated and for energizing said relay by opening said first connection, a second relay energized responsive to the energization of the first relay, means for subsequently opening the second said connection, and contacts controlled by said second relay closed prior to the opening of said second connection for establishing a third guarding connection to said test conductor and for maintaining it until said apparatus is restored to 125 normal.
55. In a telephone system, a switching apparatus having a test conductor, means for seizing said apparatus and for completing a guarding connection to said test conductor, means in said apparatus operative subsequent to said seizure to complete a second guarding connection to said test conductor, a relay having a winding included in said second connection and shunted by said first connection, means for releasing said apparatus after it has been operated and for energizing said relay by opening said first connection, a second relay energized responsive to the energization of the first relay, means for subsequently opening the second said connection, and contacts controlled by said second relay closed prior to the opening of said second connection for establishing a third guarding connection to said test conductor and for maintaining it until said apparatus is restored to 130 normal.

16. In a switch-control circuit, an impulse relay, a release relay, an operating conductor, an energizing circuit for said release relay excluding said operating conductor, contacts closed by the impulse relay on energization for closing said energizing circuit, contacts controlled by said release relay for connecting said energizing circuit to said operating circuit, contacts closed by said impulse relay upon deenergization for shunting said release relay and for bringing about a current flow over said operating conductor, a plurality of magnets arranged to respond to said current flow over said operating conductor, and means including automatic switching apparatus having testing means for connecting said operating conductor with any one of said magnets.
17. In a two-wire switch-control system, an impulse relay, a release relay, means for energizing said release relay, a magnet-operating conductor connected to said release relay, contacts closed upon the deenergization of said impulse relay for shunting said release relay to establish a current flow over said magnet-operating conductor, an electro-responsive device connected to said operating conductor and to said release relay through contacts of said impulse relay when the latter relay is energized, whereby said electro-responsive device is not affected by the potential placed on the release relay and operating conductor upon the deenergization of said impulse relay, and means for placing a potential on said operating conductor when said impulse relay is energized to operate said electro-responsive device and to shunt said release relay.
18. In an impulse transmitting system, an electro-magnetically-operated tuned reed, an electro-magnet for operating said reed, an impulse transmitting relay, a circuit including said relay and said magnet in series, said magnet having a resistance high enough so that the impulse transmitting relay is unable to energize or to remain energized in series with it, and contacts operated by said tuned reed when it is attracted by said operating magnet for shunting the associated operating magnet, whereby the deenergization of said magnet is secured and whereby the energization of said transmitting relay is secured.
19. In an impulse sender, an electro-magnetically-operated tuned reed, a magnet for operating the same, contacts controlled by said reed for controlling the action of said magnet, an impulse transmitting relay connected in series with said magnet and having impulse transmitting contacts, other impulse transmitting contacts controlled mechanically by said tuned reed, an outgoing control circuit included in one pair of said impulse transmitting contacts, and a counting switch for counting the impulses produced in said outgoing control circuit controlled from the other pair of impulse transmitting contacts.
20. In an impulse sender, an electromagnetically-operated tuned reed, a magnet for operating the same, contacts controlled by said reed for controlling the action of said magnet, an impulse transmitting relay connected in series with said magnet and having impulse transmitting contacts, other impulse transmitting contacts controlled directly by said tuned reed, and a counting switch for counting the impulses transmitted over said outgoing control circuit and driven by the impulse transmitting contacts on said relay.
21. In a combined main-office and sub-office automatic telephone system, a plurality of main offices interconnected by trunk lines to form a net work, two sub-offices interconnected by two pluralities of separately-numbered trunk groups, and a single trunk group from one sub-office to one main office for handling all main-office calls from both suboffices.
22. In a multi-office automatic telephone system including a main office and two sub-offices subsidiary to said main office, the lines of said sub-offices being assigned numbers displacing a block of numbers of said main office, inter-sub-office trunk lines, means for handling all calls between the suboffices thereover, and a group of trunk lines extending between one suboffice and said main office, and means for handling all sub-to-main and all main-to-sub calls involving both of said suboffices thereover.
23. In a combined main-office and sub-office automatic telephone system including a main office and first and second suboffices, the lines of said sub-offices being assigned numbers displacing a block of numbers of said main office, trunk lines extending from the main office to the first suboffice, means for handling all calls from the main office to either of the suboffices thereover, and trunk lines from the first suboffice to the second suboffice, and means for handling all calls to the second suboffice from the main office and from the first suboffice thereover.
24. In a combined main-office and sub-office automatic telephone system including a main office and first and second suboffices, the lines of said sub-office being assigned numbers displacing a block of numbers of said main office, trunk lines from the second suboffice to the first suboffice, means for handling all calls from the second suboffice to the first suboffice thereover, and trunk lines from the first suboffice to the main office, and means for handling all calls from both suboffices to the main office thereover.
25. In a combined main-office and sub-office automatic telephone system including a main office and first and second suboffices, the lines of said sub-offices being assigned numbers displacing a block of numbers of said main office, trunk lines between the two suboffices, means

for handling all inter-sub-office calls and calls in either direction between the second sub-office and the main office thereover, and trunk lines between the first suboffice and the main office, and means for handling all main to sub-office calls and for handling all sub-office to main-office calls thereover.

26. In a multi-office telephone system including a suboffice subsidiary to a main office, the telephone lines in each office being divided into thousand-line groups, trunk lines extending from said main office to said suboffice and terminating in thousands selectors therein, and thousands selectors in the main office having access to the thousand-line main-office groups on certain of its levels and having access on another level to said main-office to sub-office trunk lines.

27. In a two-wire switch-control system, a release relay arranged to maintain a telephone connection established when energized, an impulse conductor, means for sending impulses over said impulse conductor from either end to the other end by shunting said release relay, two electromagnets connected to opposite ends, respectively, of said impulse conductor, and switching means associated with the two ends of said impulse conductor for disconnecting the local electromagnet in either case when an impulse is being sent from one end of said impulse connector to operate the electromagnet at the other end thereof.

28. In a telephone system, a trunk line comprising two normally disconnected sections, a trunk relay group associated with said trunk line, registering apparatus separate from said trunk line and arranged to be controlled from

said trunk relay group over an impulse conductor, said trunk relay group including a release relay and a trunk-section-connecting relay both normally connected to said impulse conductor while the trunk line is in use, said release relay being energized and said connecting relay being deenergized, a line relay included in said trunk relay group having contacts for disconnecting said connecting relay and for sending an impulse over said impulse conductor by shunting said release relay each time the line relay falls back, and means in said registering apparatus for operating said connecting relay by sending an impulse from the registering apparatus to the trunk relay group over said impulse conductor while said impulse relay is operated.

29. In an impulse transmitting system, an electromagnetically-operated tuned reed, an electromagnet for operating said reed, a circuit for said magnet, contacts controlled by said reed included in the circuit of said magnet whereby the said magnet circuit is periodically altered by the reed so that the magnet is periodically energized and deenergized to keep the reed in a state of vibration, an impulse-transmitting relay having impulse transmitting contacts, and circuit connections including said impulse transmitting relay in circuit with the magnet controlling said reed so that the impulse transmitting relay operates and falls back in step with the vibrations of said reed.

In witness whereof, I hereunto subscribe my name this 5th day of June, A. D. 1924.

MARTIN L. NELSON.
